UNITED STATES PATENT OFFICE

161,828

DRY MATERIAL DISPENSER

Joseph J. Garubo, East Orange, N. J.

Application May 26, 1950, Serial No. 10,202

Term of patent 7 years

(Cl. D52—2)

To all whom it may concern:

Be it known that I, Joseph J. Garubo, a citizen of the United States, residing at East Orange, in the county of Essex, State of New Jersey, have invented a new, original, and ornamental Design for a Dry Material Dispenser, of which the following is a specification, reference being had to the accompanying drawing, forming a part hereof.

In the drawing:

Figure 1 is a top plan view of my design of a dry material dispenser;

Figure 2 is a side elevation of the dispenser;

Figure 3 is a side elevation similar to Figure 2 but with the dispenser turned 90°;

Figure 4 is a sectional view on the line 4—4 of Figure 3.

I claim:
The ornamental design for a dry material dispenser, as shown.

JOSEPH J. GARUBO.
